UNITED STATES PATENT OFFICE.

JAMES F. BRODERICK, OF CHICAGO, ILLINOIS, ASSIGNOR TO TROY LAUNDRY MACHINERY COMPANY, LTD., OF CHICAGO, ILLINOIS, A CORPORATION OF NEW YORK.

LAUNDRY-DAMPENING BOX.

1,091,558.

Specification of Letters Patent. Patented Mar. 31, 1914.

Application filed September 10, 1912. Serial No. 719,582.

To all whom it may concern:

Be it known that I, JAMES F. BRODERICK, a citizen of the United States, residing at Chicago, in the county of Cook and State 5 of Illinois, have invented certain new and useful Improvements in Laundry-Dampening Boxes, of which the following is a specification.

My invention relates in general to laundry 10 apparatus, and more particularly to a receptacle in which dampened laundry articles are subjected to pressure to distribute the moisture evenly therethrough.

After articles have been washed and dried 15 it is necessary to dampen them before they are ironed. A convenient and expeditious way of dampening articles in quite extensive use at the present time is to provide containers in the form of boxes with open tops 20 into which the dampened articles are placed, and a cover, or follower, then placed upon the articles and subjected to pressure so as to distribute the moisture evenly through the articles. In order to retain the cover 25 in the depressed position necessary to retain the articles compressed, it has heretofore been proposed to interpose pawls and racks between the follower and the box, which coöperate to lock the cover in adjusted positions relatively to the box.

The primary object of my invention is to provide an improved means for locking the cover of the box, or container, for containing dampened articles, substantially at 35 any position within the container to which the cover may be depressed in order to efficiently cause the moisture to be evenly distributed throughout the articles.

A further object of my invention is to provide an improved box, or container, of the character described, which will be simple in construction, efficient in operation, and durable in use.

My invention will be more fully disclosed 45 hereinafter with reference to the accompanying drawing, in which the same is illustrated and described as embodied in a convenient and practical form, and in which—

Figure 1 is a vertical section on line 1—1, 50 Fig. 2, the cover and locking mechanism thereon being shown in elevation; and Fig. 2 a plan view.

The same reference characters are used to

designate similar parts in the two figures of the drawing.

55

Reference character A designates a container for dampening articles which have been previously washed and dried and then dampened preparatory to being ironed. This container is preferably in the form of 60 a rectangular wooden box suitably braced so as to impart thereto the requisite strength. The container is mounted upon casters *a* so that it may be readily rolled upon the floor into and out of coöperative relation with a 65 press.

B designates a cover for the box of a size to fit within the walls thereof and to rest upon the dampened articles previously placed within the box.

70

b indicates a reinforcing strip extending diagonally across the cover B and secured thereto by any suitable means.

C' and *C*² designate links pivotally mounted at their lower ends by means of brackets *c*' and *c*² upon the strips *b* of the cover B. The links *C*' and *C*² extend in opposite directions and are pivoted by means of suitable brackets *d*' and *d*² to friction brake shoes *D*' and *D*². The brake shoes are of 80 a cross section to correspond to the inner surface of the portions of the box which they are adapted to engage. When the box is rectangular—as shown in the drawing—the brake shoes are triangular in cross section, so as to engage with a wedging action 85 within the opposite interior angles between the sides of the box. The brackets *d*' and *d*² may be secured to the shoes by any suitable means, as, for instance, bolts *d*.

90

In order that the links *C*' and *C*² may occupy the desired positions, adjustable stops *g*' and *g*² are provided upon the cover B adjacent the inner pivoted ends of the links. The stops may be so adjusted that 95 the brake shoes will tightly engage within the interior opposite corners of the box, but so as to always occupy a slightly upwardly and outwardly inclined position relatively to the cover.

100

E' and *E*² designate bell crank levers fulcrumed upon brackets *e*' and *e*² secured upon the strip *b* of the cover B. The upper end of each of the bell crank levers is provided with a handle *e* which may be grasped to 105 oscillate the lever. The lower ends of the

bell crank levers are provided with studs f' and f^2 , respectively, which extend beneath the links C' and C^2 , and engage such links when the bell crank levers are oscillated inwardly.

- The manner of using my improved dampening box is as follows: The articles which have been damped are first placed in the box, after which the cover B is inserted in the open upper end of the box and allowed to rest upon the articles, as shown in Fig. 1. The box is then wheeled under a press of any suitable construction by means of which a downward pressure is applied to the cover, so as to press the articles and cause the moisture to be evenly distributed through them. H, in Fig. 1, indicates the plunger of the press, the rest of the press not being disclosed, as it is unnecessary to do so in order that the construction and operation of my invention may be fully understood. As the cover B is moved downwardly under the action of the press, the brake shoes D' and D^2 move downwardly by gravity along the inner opposite angles of the box. When the cover has been depressed sufficiently, the plunger of the press is elevated and the box rolled away so that another box may be placed in operative relation to the press. Immediately upon the elevation of the plunger of the press the tendency of the articles to expand and lift the cover causes the brake shoes to be tightly wedged against the opposite interior corners of the box, owing to the toggle action of the links C' and C^2 . The frictional engagement, together with the wedging action, of the brake shoes with the inner opposite angles between adjacent sides of the box securely retain the cover in the depressed position to which it has been moved by the press, so that the articles are held compressed and the moisture evenly distributed through them. The surfaces of the brake shoes and the portions of the surfaces of the box to which they engage are of such material as to insure the frictional action necessary to lock the cover. When the box is made of wood, and the brake shoes also of wood, the moisture imparted to the box from the damped articles placed therein will insure the frictional contact between the shoes and box necessary to firmly lock the cover in substantially any depressed position to which it may have been moved by the press. The position at which the cover will be locked is of course slightly above that to which it is moved by the press, inasmuch as the cover rises slightly to effect the clamping engagement of the brake shoes with the inner surfaces of the box. When it is desired to remove the articles from the box, the handles e of the bell crank levers E' and E^2 are grasped by the hands of an operator and pulled toward each other.

This oscillates the bell crank levers so that the studs f' and f^2 thereon are moved upwardly and engage beneath the links C' and C^2 , so that the latter are swung upwardly and the brake shoes thereby disengaged from the opposite corners of the box. The cover may then be entirely removed from the box by lifting upwardly on the handles e of the bell crank levers.

From the foregoing description it will be observed that I have invented an improved box for containing damped clothes, or for similar objects, in which the cover will be positively retained in any desired position within the box without the employment of pawls and rack bars, and consequently without the limitations as to the positions in which the cover may be locked incident to the use of pawls and rack bars.

While I have described more or less in detail the specific form in which I have illustrated my invention as embodied, yet I do not wish to be understood as limiting myself thereto, as I contemplate changes in form, proportion of parts, and substitution of equivalents, as circumstances may require or as may be deemed expedient.

I claim:

1. The combination with a receptacle of the character described, of a cover fitting within said receptacle, a plurality of frictional brake shoes adapted to engage opposing portions of the inner surface of said receptacle, and upwardly inclined links pivotally connecting said shoes with said cover.

2. The combination with a receptacle of the character described, of a cover fitting within said receptacle, frictional brake shoes conforming to and adapted to engage opposite portions of the inner surface of said receptacle, and links pivotally connecting said shoes with the upper surface of said cover, the said links being inclined upwardly from the cover to the shoes.

3. The combination with a receptacle of the character described, of a cover fitting within said receptacle, frictional brake shoes conforming to and adapted to engage opposite portions of the inner surface of said receptacle, links pivotally connecting said shoes with the upper surface of said cover, and means for disengaging said shoes from the receptacle to permit said cover to be lifted.

4. The combination with a receptacle of the character described, of a cover fitting within said receptacle, frictional brake shoes conforming to and adapted to engage opposite portions of the inner surface of said receptacle, upwardly inclined links pivotally connecting said shoes with the upper surface of said cover, and unlatching devices engaging said links to actuate them to disengage said shoes from the inner surface of the re-

ceptacle, thereby permitting the cover to be lifted.

5. The combination with a receptacle of the character described, of a cover fitting within said receptacle, frictional brake shoes conforming to and adapted to engage the inner surface of said receptacle, links pivotally connecting said shoes with the upper surface of said cover, unlatching devices 10 gaging said links to actuate them to disengage said shoes from the inner surface of the receptacle, and handles on said devices for operating them and for lifting said cover out of the receptacle.

15. 6. The combination with a receptacle of the character described, of a cover fitting within said receptacle, frictional brake shoes conforming to and adapted to engage opposite portions of the inner surface of said receptacle, links pivotally connecting said shoes with the upper surface of said cover, bell crank levers pivotally mounted on the upper surface of said cover, studs on said levers adapted to engage said links to release

20 25 said shoes from engagement with the inner surface of the receptacle, and handles on said bell crank levers to oscillate them to effect the release of the brake shoes, and for

facilitating the lifting of said cover out of the receptacle.

30 7. The combination with a receptacle of the character described comprising side walls joining each other at acute angles, of a cover fitting within said receptacle, frictional devices carried by said cover conforming to 35 and adapted to engage within the angles between adjacent side walls of said receptacle, and means operatively engaging said devices for disconnecting them from the inner surface of said receptacle and for lifting the 40 cover out of the receptacle.

8. The combination with a receptacle of the character described, of a cover fitting within said receptacle, frictional brake shoes conforming to and adapted to engage opposite portions of the inner surface of said receptacle, links pivotally connecting said shoes with the upper surface of said cover, and adjustable stops on said cover for limiting the downward movement of said links. 45

In testimony whereof, I have subscribed my name.

JAMES F. BRODERICK.
